DESIGN FOR A PEDESTAL FOR OIL BURNERS OR THE LIKE

Reginald W. Beckett, Elyria, Ohio

Application December 15, 1938, Serial No. 81,786

Term of patent 14 years

To all whom it may concern:

Be it known that I, Reginald W. Beckett, a citizen of Canada, residing at Elyria, in the county of Lorain and State of Ohio, have invented a new, original, and ornamental Design for a Pedestal for Oil Burners or the like, of which the following is a specification, reference being had to the accompanying drawing, forming a part thereof.

In the drawing:

Figure 1 is a perspective view of a pedestal for oil burners or the like, showing my new design; Figure 2 is a top plan view thereof; and Figure 3 is a sectional view taken substantially on the line 3—3 of Figure 2.

I claim:

The ornamental design for a pedestal for oil burners or the like, substantially as shown.

REGINALD W. BECKETT.
